SPARK PLUG CLEANING APPARATUS

Robert K. Christie, Toledo, Ohio, assignor to
 Champion Spark Plug Company, Toledo, Ohio,
 a corporation of Delaware

Application July 30, 1947, Serial No. 764,860

9 Claims. (Cl. 134—152)

1

This invention relates primarily to spark plug cleaning means of the type in which a chemical solution, preferably containing an abrasive material, is discharged in spray form against the electrodes and surfaces at the firing end of a spark plug which become coated with fuel deposits in service.

An object of the invention is the provision of a novel apparatus of this class that is operable in a simple and rapid manner to efficiently and economically clean spark plugs of carbon and other deposits accumulated on and within the firing end portions thereof in use.

Another object of the invention is the provision in an apparatus of this class of simple and efficient means for rotating a spark plug about its longitudinal axis during cleaning, whereby all surfaces that are subject to being coated in use are effectively cleaned by the spraying action.

Other objects of the invention will be apparent from the following detailed description, and from the accompanying drawings illustrating one embodiment thereof, in which:

Fig. 1 is a perspective view of an apparatus with a spark plug mounted in cleaning position and with the turning head for the plug in raised or inoperative position; Fig. 2 is a similar fragmentary view thereof with the turning head in lowered or operative position; Fig. 3 is a different fragmentary perspective view of the apparatus with the turning head raised and the operator in the act of placing a spark plug in position for cleaning; Fig. 4 is an enlarged fragmentary central vertical section of the apparatus on the line 4—4 in Fig. 2 with the turning head lowered into operative turning engagement with a spark plug to be cleaned and with parts in full; Fig. 5 is an enlarged bottom perspective view of the cover plate assembly; Fig. 6 is an enlarged fragmentary sectional detail similar to a portion of Fig. 4 showing the spraying means; Fig. 7 is a top plan view of the spray head cover with associated nozzles, and Fig. 8 is a section on the line 8—8 in Fig. 6.

Referring to the drawings, 1 designates a table or other suitable support having a top 2 provided with a rather large opening 3 (Fig. 4) therethrough. This opening is closed by a removable base plate 4 that overlaps the top marginal edge of the opening 3 and is secured thereto by screws 5. The plate 4 has an opening 6 therethrough closed by a top or cover plate 7 which is centered within the opening by an interfitting flange 8 and is clamped to the top marginal edge of the plate 4 by a series of bolts 9. A bushing 10 is fitted into a receiving opening

in the plate 7 and is adapted to rotatably receive the threaded shell end of a spark plug A. The upper end of this bushing is cupped to permit the spark plug shell to seat down therein and its side edge is flanged over the marginal edge of the plate opening. The firing end of the plug is exposed below the bushing.

Suspended below the bushing 10, in centered relation thereto by a plurality of lugs 11 dependent from the bottom of the plate 7, is a spray head unit 12. This unit comprises, in the present instance, a ring 13 attached to the lugs 11 by a plurality of screws 14, a base member 15 fixedly secured in the ring and suspended therefrom with its top recessed to form a chamber 16 and a cover plate 17 that closes the top of said chamber and carries a plurality of liquid spray nozzles 18 directed toward the adjacent end of a spark plug mounted in the bushing 10. These nozzles open at their inner ends to the chamber 16. In the present instance, four nozzles 18 are provided preferably of varying heights with different sized orifices, one nozzle being at the center of the group and positioned to direct its spray straight up into the spark plug end in slightly offset relation to its axis, and the others being arranged around the center nozzle and inwardly and upwardly inclined to direct their respective streams at different angles into the plug end. An air nozzle 19 projects upward from the bottom of the chamber 16 is fixed axial relation to each nozzle 18 in spaced relation to its bore, so as to have its discharge therein and to provide a suction space therebetween, as is common with suction type nozzles. In the present instance, the upper end of each air nozzle 19 is of less diameter than the bore of the associated nozzle 18 and projects to a slight extent therein with a suction space therebetween.

The several air nozzles 19 are in communication with a suitable air pressure source through bores 20 and branches therefrom provided in the base member 15 and through a connection 21. A normally closed control valve 22 is interposed in the connection 21 and has an operating stem 23 projecting up through the valve casing and a short distance above the level of the plate 7 to be operated, as hereinafter described. The connection 21 is carried by the top plate 7 and has a part on top of such plate, as shown in Figs. 1 and 4, to which a tube or flexible hose 24 from a supply source may connect.

The suction chamber 16 is in communication with a container 28 for a cleaning solution through a tube 29 which extends from the bottom of the chamber down into the container to near

its bottom, as shown in Fig. 4. This container comprises an open top tank that is attached at its upper end to and is suspended from the lower marginal edge of the base plate opening 6 by a ring 30 and screws 31. The bolts 9 also may be used for this purpose. A vent pipe 32 extends from the top portion of the container and connects through an opening in the rear end portion of the base plate 4 with a stack 33 rising therefrom, the lower end of the stack being mounted in a standard 34 on said plate.

The contents of the container 28 are agitated by a paddle 35 having connection with a shaft 36, whereby a wobble action is imparted thereto by a rotation of the shaft. This shaft is mounted in a bearing attached to the side portion of the container and is driven by a motor 37 (Fig. 1) through a suitable connection.

The drive head 40 for imparting rotation to a spark plug, when mounted in cleaning position in the bushing 10, is carried in upright position by two pairs of parallel bars 41, one pair at each side, with the rear ends of both pairs pivoted in vertically spaced relation to the standard 34 and with the front ends thereof correspondingly pivoted to respective sides of the head. The head 40 may thus be raised and lowered by a swinging action and maintained in upright position during such movement.

The head 40 is hollow with its lower end open to seat down on the top plate 7 around the bushing 10 and is provided interiorly of its lower end portion with a part 42 forming a vertical bearing for a clutch sleeve 43. This sleeve is mounted for rotary and axial movements in the bearing, the axial movements being limited by a screw pin 46 engaging in an annular circumferential groove 45 in the sleeve. The sleeve is yieldingly held in lowered position relative to the part 42 by a coiled compression spring 46, which has its upper end thrust against a stationary part of the head and its lower end thrust against a drive part 47 in driving engagement with the upper end of the sleeve.

In the upper portion of the head 40 is mounted a small slow speed electric motor 48 which may be connected to any suitable electrical source and has driving connection at 49 with a vertical shaft 50 which has splined driving engagement with the part 47.

The lower end of the sleeve 43 is internally of hex-form complementary to the customary hex shell portion of a spark plug A and fits down thereover when the head 40 is in lowered or operative position, as shown in Fig. 4, so that a turning of the sleeve will cause a turning of the spark plug on its seat in the bushing 10. The head 40 is retained in lowered position by a hand operated latch 51 that is pivoted to the front side of the head and engages a stationary catch member 52 on the plate 7. A spring 53 acts on the latch 51 to cause it to have snap engagement with the catch 52 when the head is in lowered position.

The head 40 is caused to be drawn upward, or at least is counterbalanced as to its weight, by a cable 55 that extends upward therefrom to and winds on a spring actuated retrieving drum 56 supported by the stack 33. During the final portion of a lowering movement of the head, a bracket 57 thereon strikes and depresses the valve stem 23 to cause an opening of the air valve 22 to supply air pressure to the air nozzles 19.

The raising movement of the head 40 is limited by a cross-piece 60 that is carried by the lower

set of bars 41 striking a stop cushion 61 provided on a rod 62. This rod is hinged to and extends upwardly from the top plate 7, as shown in Fig. 4. In an operation of the apparatus, a suitable cleaning liquid is placed in the container 28 and a spark plug A to be cleaned is mounted in the bushing 10. The head 40 is then lowered to cause the clutch sleeve 43 to extend down over the upper end portion of the plug and to have turning engagement at its lower end with the hex portion of the plug. The head is held in this position by engagement of the latch 51 with the catch 52. The final lowering movement of the head causes the bracket 57 thereon to engage and depress the valve stem 23, thus causing an opening of the air valve to effect a discharge of air through the air nozzles 19 and into and through the nozzles 18. The suction thus created causes the cleaning liquid to be drawn from the container 28 up into the chamber 16 and discharged therefrom through the nozzles 18 in the form of spray jets which are directed upwardly in different positions and at different angles against the open firing end of the plug. The turning of the plug during this spraying action causes the cleaning spray to be directed into all portions of the hollow firing end of the plug and against the electrodes so as to effect a thorough and rapid cleaning thereof. The cleaning having been completed, the latch 51 is disconnected from its catch and the turning head 40 is raised to expose the spark plug to permit its removal from the bushing 10 and the insertion therein of another plug to be cleaned. After a cleaning operation, the plug may be washed of the cleaning liquid in any suitable manner. The clutch sleeve 43 has a yielding axial movement to adapt it to accommodate itself to the position of the plug and to cause a cushioned engaging action of the sleeve and plug. The speed of the motor and the driving connection between it and the clutch sleeve are such as to cause a slow turning of a spark plug during a cleaning action.

The apparatus is simple to clean, as the container 28 is readily accessible for the purpose of filling or cleaning by simply removing the top plate 7 and disconnected assembly, thus exposing not only the interior of the container but also the spraying parts.

I wish it understood that my invention is not limited to any specific construction, arrangement or form of the parts, as it is capable of numerous modifications and changes without departing from the spirit of the claims.

Having thus described my invention, what I claim as new, and desire to secure by United States Letters Patent, is:

1. In a spark plug cleaning apparatus, a spark plug support, means for rotating a supported spark plug about its longitudinal axis and including a driven clutch sleeve movable into and out of driving engagement with a supported spark plug, means for directing a cleaning solution against the firing end of the plug while being rotated, and means operable to cause the last-mentioned means to operate when the driven clutch sleeve is moved into driving engagement with a supported spark plug.

2. In a spark plug cleaning apparatus, a spark plug support, a clutch member for engaging a supported plug, means carrying said member for movement into and out of driving engagement with a supported spark plug, means for driving said member to rotate an engaged spark plug,

spray means for directing a cleaning solution against the firing end of a plug when rotated, and control means for the spray means actuated by said carrying means, at a predetermined point in its movement, to effect a spraying operation.

3. In a spark plug cleaning apparatus, a support having an opening therein, a plate for closing said opening, a spark plug support carried by the plate and permitting rotation of a supported plug with both ends exposed, means carried by the plate for directing a plurality of streams of cleaning solution against the firing end of the plug, means for containing a solution to be sprayed, means movable into and out of position to engage the opposite end of a supported plug and to impart rotation thereto, and means automatically operable to render the spraying means operative when said last-mentioned means is in a predetermined position of its movement.

4. In a spark plug cleaning apparatus, means for supporting a spark plug for rotation about its longitudinal axis with its firing end exposed, a hollow head adapted to seat around the upper portion of a spark plug supported by said means and vertically movable into and out of enclosing relation to the plug, means guiding said head for swinging movements in a vertical plane and operable during said movements to maintain its vertical axis parallel to the axis of a supported plug, a clutch sleeve rotatably mounted in said head for engaging and rotatably driving a spark plug on said support when said head is in lowered position, means carried by the head for rotating said sleeve, and means for directing a cleaning solution forcibly against the exposed plug end when rotated.

5. In a spark plug cleaning apparatus, means for supporting a spark plug for rotation about its longitudinal axis with its firing end exposed in cleaning position and its other end projected therefrom, a head guided for arcuate movement in a vertical plane into and out of operative relation to the projected end of a supported plug, a rotatable clutch sleeve mounted in said head for receiving the projected end of a plug and to have driving engagement therewith when the head is

in operative position, means operable to rotate said sleeve, and means for directing a cleaning solution forcibly against the exposed plug end when rotated.

5 6. A combination as called for in claim 5, wherein the clutch sleeve is mounted for yielding axial movements in the head to adapt itself to the position of a spark plug and the axes of the head and sleeve are maintained in vertical position during their arcuate movements.

10 7. A combination as called for in claim 5 together with means yieldingly influencing movement of the head to inoperative position, and releasable catch means for holding the head in operative position.

15 8. In a spark plug cleaning apparatus, a spark plug support, a female clutch member for engaging a supported plug, a carrying head for said member operable to move it arcuately in a vertical plane into and out of driving engagement with a supported spark plug, means carried by said head for driving said member to rotate an engaged spark plug, and spray means for directing a cleaning solution against the firing end of a plug when rotated.

20 25 9. A combination as called for in claim 8, wherein the clutch member has yielding engagement with the spark plug axially thereof.

ROBERT K. CHRISTIE.
